(57) CLAIM

What is claimed is the ornamental design for a razor, as shown and described.

DESCRIPTION

FIG. 1 is a top-right-front perspective view of a razor, showing the new design;

FIG. 2 is a rear elevational view thereof;

FIG. 3 is a front elevational view thereof;

FIG. 4 is a bottom plan view thereof;

FIG. 5 is a top plan view thereof;

FIG. 6 is a right-side elevational view thereof (the left-side elevational view is a mirror image thereof); and,

FIG. 7 is a bottom-right-rear perspective view of a razor, showing the new design.

The broken lines illustrate portions of the razor and form no part of the claimed design.
